DOOR HINGE

Anestis Foltis, Jackson Heights, N. Y.

Application February 11, 1947, Serial No. 727,823

5 Claims. (Cl. 16—68)

1

My invention is an improved hinge for doors and the like, supported to turn about vertical axes; and especially a hinge for actuating a door to swing to closed position after it has been opened.

The principal object of the invention is to provide a hinge containing means for storing up energy when the door, for example, which it mounts is swung to one side; and to expend this energy to impel the door in the opposite direction as soon as it is released; the hinge comprising parts to enclose a body of air acting as a pneumatic cushion, for retarding the reverse motion of the door and thus render the closing soft, slow and noiseless.

Another object of this invention is to provide a hinge of this type that is simple in its construction, certain and efficient in operation; and embracing relatively few parts, so that it can be easily produced at relatively low manufacturing cost.

The character of the invention is described in the following specification, and the novel features are defined in the appended claims. This disclosure, however, sets forth only the best forms of the invention now known to me, and numerous changes may be made in practice without deviating from the principle of the invention, or omitting any of the essential and distinctive features thereof.

On the drawings:

Figure 1 is a top view of a hinge according to this invention in operative position.

Figure 2 is a front elevation thereof.

Figure 3 is a section substantially on line 3—3 of Figure 1.

Figure 4 shows in elevation the parts indicated in Figure 3.

Figure 5 is a horizontal section on line 5—5 of Figure 2.

Figure 6 is a view similar to Figure 1, showing the door with hinges according to this invention after it has been opened.

Figure 7 is a horizontal section on line 7—7 in Figure 6.

Figure 8 is a top view similar to Figure 1 of a modification.

Figure 9 is a front elevation of the same.

Figure 10 is a vertical section on line 10—10 of Figure 9.

Figure 11 is a horizontal section on line 11—11 of Figure 9.

Figure 12 is a view of this modification with the parts in the same relative positions as on Figure 7.

2

Figures 13, 14 and 15 are sectional details of more modifications of the structure of the hinge.

Figure 16 is a top view similar to Figure 1 of another embodiment of the invention; and Figure 17 is a front elevation of the same.

Figure 18 is a section on line 18—18 of Figure 16.

Figure 19 shows this particular hinge with the parts distended and the parts seen in outside elevation.

Figure 20 shows the same hinge with the two sides distended and the internal parts in section.

Figure 21 is a front elevation of an additional modification of the hinge of this invention.

Figure 22 is a view of the hinge of Figure 21 showing the parts in vertical section.

Figure 23 is a view of the hinge of Figure 21, seen from the right of the plane of the line 20 23—23.

Figure 24 shows this hinge in the same plane, but with the parts in vertical section.

Figure 25 is a view of the hinge of Figure 21 with the parts distended in the same way as on 25 Figure 7; and

Figure 26 is a horizontal section on line 26—26 of Figure 22.

My improvement comprises a hinge made up in two halves, one of which carries a tubular section or bearing 1, and the other a pair of tubular sections or bearings 2 and 2'; and the halves are connected with the bearings 2 and 2' and the bearing 1 in alignment, the latter being in between the bearings 2 and 2', as presented in Figures 1 to 7. The bearing 1 is made integral with a flat leaf 3, to which it is united near the middle of one edge; and similarly the bearings 2 and 2' of the other half are united to one edge of a leaf 4. The leaf 3 is secured to the inside face of the frame or jamb 5 of a doorway, window opening or the like, and the leaf 4 of the other half is similarly affixed to the edge of the door, window or other member 6, which is to be mounted by means of said hinges. A part of the wall 45 containing the doorway or window opening, is indicated by the numeral 7. Both the leaves 3 and 4 fit into recesses on the adjacent faces of the frame 5 and member 6, so as to be flush with these faces when secured in position. When the door or window is closed the two halves of the hinge are in the position indicated in Figures 1 and 2, and when the door or window is opened, the two halves of the hinge are unfolded or distended, as indicated in Figures 6 and 7.

55 Inside the bearings 1 and 2 and 2' is a tubular

element 8 which, among other things, serves the same purpose as a hinge pin and connects the two halves of the hinge in pivoted relation. This element 8 can turn freely in the sections or bearings 2 and 2', but it is anchored and held rigid with respect to the bearing 1 by a binding screw 9. The element 8 is in the form of a hollow tubular casing and also serves as a pump cylinder within which is a piston or plunger 10, which is in the lower half of the element 8. In the upper end of the element 8 is a head 11 connected to the piston 10 by a rod 12, the outer extremity of the head 11 having a projecting rim 11a, which abuts the top of the element 8 when the leaves of the hinge are folded together, and the door is closed. The stem 12 may be integral with the head 11 and screwed into a threaded bore in the piston 10. In the side of the head 11 is affixed a stud or screw 13 which projects out through a longitudinal slot 14 on one side of the element 8; and this stud or screw head 13 is also received in a spiral or inclined cam slot 15 in the upper bearing 2'. Hence, whenever the two halves of the hinge are turned on the element 8 as a journal, the slot 15 will cause the head 11 and piston 10 to move axially within the element 8 and this movement will carry the pin 13 lengthwise in the slot 14.

Adjacent the upper end of the bearing 1 the element 8 has an inside collar 8a through which the rod 12 passes. The plunger 10 may be encircled by a pair of packing rings 10a in grooved seats formed in the piston 10 so that the latter has a leak-proof fit in the casing 8. Between the piston 10 and the flange 8a, the stem 12 is encircled by a spiral compression spring 16. The lower end of the element 8 is closed by a screw cap 8b, that has a recess 17 terminating at the inner end in a cone-shaped seat for a ball valve 18, which is held against the seat by a suitable spring 19 retained in the recess 17 in any suitable manner. Communicating with the seat is a duct or passage 20, by which air can enter the casing 8 when the piston 10 is lifted.

When the door 6, for example, is opened as by revolving counterclockwise in Figure 1, or to the right in Figure 2, the one half of the hinge is turned so that the bearings 2 and 2' and leaf 4 revolve with respect to the bearing 1, and the slot 15 in the bearing 2' lifts the piston 10 and head 11 by reason of its action on the stud 13, which is free to slide upward in the straight slot 14 in the side of the element 8. While the piston is thus being lifted the spring 16 is compressed; and the ball valve 18 is unseated and air passes through the port 20 into the lower part of the element 8 below the piston 10. When the door is released the spring 16 impels the piston downward, and the action of the stud 13 on the lower inclined edge of the cam slot 15 now causes the two halves or leaves 3 and 4 of the hinge to turn towards folded position and swing the door shut. This operation is brought about very slowly, because valve 18 is now closed and the air trapped in the lower part of the element 8 serves as a cushion or dashpot, resisting the downward motion of the piston, and is expelled little by little past the valve 18 and through the restricted opening 20. I prefer to make the valve fit its seat in the recess 17 loosely enough to permit the discharge of the air in this way, but obviously a separate outlet opening in the cap 8b may be formed, if desired. The door thus closes easily and without slamming.

The flat leaves 3 and 4 of the hinge can be secured to the side of the frame and the door or

window by screws or the like, as shown at 21.

In Figures 8 to 12 inclusive, the leaf 4 of one of the halves affixed to the member 6 is shown as having a ridge or rib 2a along the outer edge, and at the two extremities of the ridge the leaf 4 has bearing rings 2c and 2d at its ends. The leaf 3 of the other half has a bearing 1' that takes the place of the tubular element 8 and is substantially the same length as the leaf 4 and is connected to the leaf 4 by means of the bearings 2c and 2d. This bearing 1' has the longitudinal slot 14 at its upper end for the stud or screw 13 affixed to the head 11; and the rib 2a of the hinge has a projection 2b adjacent the top which curves around the outside of the bearing 1' and bears the cam slot 15 to engage the outer extremity of the stud 13. The inside of the bearing 1' has the shoulder 3a. The top of the bearing 1' engages the bearing 2c directly; this bearing 2c being bent inward, and the lower end of the bearing 1' is above the bearing 2d, but is threaded to receive the cap 8a. The latter is received in the bearing 2d and has a rim 3b that abuts the lower edge of the bearing 2d. The action of this hinge is the same as that of the first form. When the door or the like is closed, the hinge is in folded position with the stud 13 at the lower ends of the slots 14 and 15, as shown in Figures 8, 9 and 10. As the door is opened the parts of the hinge are moved towards the position shown in Figure 12, the stud 13 being forced upward by the cam slot 15, and moving along the slot 14 to lift the piston in the bearing 1' on its suction stroke. When the door is released the spring 12 returns the hinge and the door to original position, and the piston 13 is cushioned as before by the air between the piston and the lower closure cap 8a.

In Figure 12 the plane of section is in the surfaces of the leaves 3 and 4 in contact with the parts 5 and 6, these surfaces being presented to the observer.

In Figure 13 the ball valve 18 is located in the closure plug 8c, in the same way as before, but this plug 8c is longer and has a smaller chamber 28a connected to the recess 17 by the duct 28 and to the outer air by ducts 28'. The duct 28 at the chamber 28a has an enlarged opening to cooperate with a pointed screw 22 which regulates the passage of the air through this plug.

In Figure 14 the piston 10 is shown with a recess 17a having a conical seat for the ball valve 18; and the part of the recess 17a beyond the seat of the valve 18 is extended and communicates with the space around the rod 12 through ducts 17b. The cap 8d, which is screwed into the journal 1', has a small opening 28b, and this cap is engaged by the bearing ring 2d of the leaf 4. The valve 18 is arranged to fit loosely on its seat, as does the valve 18, in the form shown in Figures 1 to 6 inclusive, so that air can pass this valve both ways.

In Figure 15 the piston is shown as having the same construction as in Figure 14, carrying the ball valve, but the plug or cap 8e is the same as in Figure 13 only shorter; an air chamber 20a, a port 20 connecting it with the interior space below the piston, ducts 20' to connect the chamber to the outer air, and an adjustable metering pin or screw 22 to control the passage of air through this cap.

In the embodiment of Figures 16 to 20 inclusive, the leaf affixed to the door 6 has a lower bearing 2e and an upper bearing 2f; and the leaf 3 has a single bearing 1'' with its lower end separated from the bearing 2e when the door is shut.

5

The hollow journal 8 is fixed in the bearing 1'; and the lower end of the bearing 2f has a cam edge 15a engaging a corresponding cam edge 15b on the upper edge of the bearing 1''. The head 11 has the stud 13 projecting through a vertical slot 13' in the journal 8 and into a straight horizontal slot 15a in the bearing 2f. Figures 19 and 20 show the operation, these two views presenting to the observer the faces of the leaves 3 and 4 that are in contact with the frame 5 and door 6. 10 When the door is opened, the cam action of the edges 15b and 15c cause the bearings 2f and 2e to move upward so as to lift the door 6. The piston 10 draws air in through the closure 8b. When the door is released, it will close by gravity, with 15 the cam edge 15b sliding along the downward inclined part of the cam edge 15c. The air in the journal 8 now serves as a cushion. No spring is necessary in the journal 8.

In the form illustrated in Figures 21 to 26, the bearings 1 and 2 on the leaves 4 and 3 respectively are the same as indicated in Figures 1 to 7; but the upper bearing 2g of the leaf 4 has an upper cam edge 15d. The head 11 has a cam projection 11b overlapping the top of the journal 8 and engaging the cam edge 15d. The piston and valve construction is the same as depicted on Figures 3 and 7 for instance, but the stem 12 connecting the piston to the head 11 is square or polygonal, and the hole in the web 8a is shaped to prevent the rod 12 and head 11 from turning. When the door is opened, the head 11 and piston are actuated to draw air in through the valve controlled opening 20, the head being lifted to the position shown in Figure 25. This view is of the same character as Figure 20, presenting the same faces of the leaves 3 and 4 to the observer. The door however, is not lifted, but always swings at a constant level.

Having described my invention, what I believe to be new is:

1. A hinge construction comprising two halves, one of which carries a hollow cylindrical journal rigidly mounted therein and the other of which has means for pivotally encircling said journal at the opposite ends thereof, a piston movable in said journal and held against turning therein, cam means carried by said other half to engage and move the piston, a spring in said journal to oppose the movement of the piston, a head connected to the piston and having a projecting rim abutting and closing one end of the journal

6

when the piston is retracted by the spring, a cap closing the other end of the journal, and means in the cap for admitting air to said journal.

2. A hinge construction comprising two halves one of which carries a hollow cylindrical rigidly mounted journal and the other has means for pivotally encircling said journal at the opposite ends thereof; a movable piston in said journal, the latter having a straight slot and the piston a fixed stud projecting into said slot so that the piston can be moved lengthwise but is held against turning, cam means carried by the other half to engage and move the piston, a head connected to the piston and having a projecting rim abutting and closing one end of the journal when the piston is retracted, a cap closing the other end of the journal and means in the cap for admitting air to the journal.

3. The hinge construction according to claim 2 wherein the means for encircling the journal comprises rings carried by the other half, and the cam means comprises a part between said rings with a cam slot therein.

4. The hinge construction according to claim 2 in which the one half carries a hollow bearing with the journal therein and the other half has a bearing and the cam means comprises abutting inclined edges on said bearings.

5. The hinge construction according to claim 2 in which the one half carries a bearing with the journal therein and the other half carries a bearing encircling said journal, and the cam means comprises an inclined edge on said last-named bearing and a cam projection on said head.

ANESTIS FOLTIS.
